UNITED STATES PATENT OFFICE.

ROSE KOWALCZUK, OF BUFFALO, NEW YORK.

LAUNDERING TUB.

1,414,138.

Specification of Letters Patent Patented Apr. 25, 1922.

Application filed April 13, 1920. Serial No. 373,575.

To all whom it may concern:

Be it known that I, ROSE KOWALCZUK, a citizen of Poland, residing at Buffalo, in the county of Erie and State of New York, have 5 invented certain new and useful Improvements in Laundering Tubs, of which the following is a specification.

This invention relates to laundering tubs and more particularly to improvements in 10 tubs especially intended for domestic use in the boiling of clothes. The principal object is to provide a tub in which the water may be maintained at boiling temperature but the escape of steam, both while the 15 clothes are being boiled and while they are being removed, is substantially eliminated, thereby promoting the comfort and convenience of the laundress and aiding the sanitary condition of the basement or laund- 20 dry room. A further object is to provide a tub which, along with the above stated advantage, may, in draining, serve incidentally for the effective flushing and cleaning of the drain pipe to which the other tubs of the group 25 may be connected.

With the above objects in view, the invention consists generally in the combination with the tub of a burner, a movable lid or cover, a means of water supply controlled 30 externally of the tub and means for distributing the water uniformly over the area of the tub. The invention consists further in certain details of structure and arrangement which will be pointed out as the de- 35 scription proceeds.

A boiling tub in which the features of the invention are incorporated is illustrated in the accompanying drawing, wherein:

Figure 1 is an elevation showing a group 40 of laundry tubs and at the right end thereof a boiling tub in accordance with the invention.

Figure 2 is a bottom plan view of the lid or cover.

Figure 3 is a detail sectional view on the line 3—3 of Figure 2.

Similar characters of reference designate corresponding parts throughout the views.

The improved boiling tub is preferably 50 one of the group of stationary tubs such as form a part of the equipment of modern laundry basements, and is so shown, but it may, of course, be constructed as a separate and independent unit.

According to the invention, the boiling

tub, as 1, has below it and close to its bottom, so as to impart the requisite heat thereto, a burner 2 of suitable construction, i. e., a gas or electric burner. Said tub is also provided with a lid or cover 3 which may 60 be removed to disclose the contents of the tub and enable the removal of the clothes after boiling. A source of water supply is arranged above the cover 3 and in the embodiment shown, where the tub is stationary, 65 consists of the usual water service pipe 4 and spigot 5.

In the construction preferred, provision is made for delivering the water to the tub while the cover 3 is closed and for causing 70 the water, as delivered, to be distributed substantially over the area of the tub. For this purpose the cover 3 carries, adjacent its underface, a suitable water distributing device 6 provided with a nipple 7 which 75 projects through said cover and is connected externally, as by a removable hose section 8, to the spigot 5. The device 6 may with advantage consist of a tubular ring provided throughout its extent with closely associated 80 perforations through which the water is discharged in numerous small jets and in all directions.

The tub 1 is provided with an outlet pipe 9 which, where, as shown and preferred, the 85 tub forms one of a group of stationary tubs, may be connected to the drain pipe 10, common to the group.

In use, the cover 3 is removed and the tub 1 is filled to the desired level with cold water 90 from the spigot 5. The clothes are then put in the tub and the cover 3 is closed, the hose section 8 being then fitted to the nipple 7 and spigot 5. The burner 2 is then ignited to heat the water and the cover 3 prevents 95 the escape of steam when the water attains boiling temperature. When the clothes have been boiled sufficiently long, the burner 2 is cut off and the spigot 5 is operated for a momentary interval to supply a small volume 100 of cold water to the device 6 which distributes it substantially over the area of the tub. This cold water forms a layer or film on the surface of the boiling water without substantially reducing its temperature and such layer or film of cold water is effective to absorb or blanket the steam. The cover 3 may then be opened without the liability 105 of steam escaping, in appreciable measure, from the tub, whereupon the clothes may be 110

removed or transferred to another tub for a different operation such as rinsing or bluing. In connection with the removal of the clothes the plug is withdrawn from the outlet pipe 9 and the water, at boiling temperature, or nearly so, flows through the drain pipe 10 flushing it, and by virtue of its temperature, cleaning it of any grease or like deposits which may have been carried over 10 with the water from the other tubs.

When not desired for use as a boiling tub, in the manner described, the tub 1 may be used in the same way as the remaining, and usual, laundry tubs.

Having fully described my invention, I 15 claim:

The combination of a tub in which water may be maintained at boiling temperature, a movable lid by which said tub may be closed, and means within the tub for so distributing cold water that in a momentary interval it will form a thin stratum upon the boiling water and substantially over the area of the tub. 20

In testimony whereof I have affixed my 25 signature.

ROSE KOWALCZUK.
